UNITED STATES PATENT OFFICE

MELCHIOR ZWICKY, OF BERKSHIRE HEIGHTS, PENNSYLVANIA, ASSIGNOR TO BERKSHIRE KNITTING MILLS, OF WYOMISSING, PENNSYLVANIA, A CORPORATION OF PENNSYLVANIA

DESIGN FOR A KNITTED FABRIC

Application filed October 1, 1931. Serial No. 41,281. Term of patent 14 years.

To all whom it may concern:

Be it known that I, MELCHIOR ZWICKY, a citizen of the United States of America, residing at Berkshire Heights, in the county of Berks and State of Pennsylvania, have invented a new, original, and ornamental Design for a Knitted Fabric, of which the following is a specification, reference being had to the accompanying drawing, forming part thereof.

The figure is a plan view of a knitted fabric, showing my new design, comprising an

arrangement of elongated six-sided figures set forth in bold relief by a field of small figures in a manner suggestive of a gothic design. In the drawing the fabric is shown enlarged approximately 1½ times actual size, but which in reduction to patent size will show the fabric approximately actual size.

I claim:

The ornamental design for a knitted fabric as shown and described.

In testimony whereof I affix my signature.

MELCHIOR ZWICKY.
